UNITED STATES PATENT OFFICE.

JOHN G. VENN, OF JACKSON, MICHIGAN, ASSIGNOR TO JACKSON CUSHION SPRING COMPANY, OF JACKSON, MICHIGAN.

SPRING STRUCTURE.

1,213,980.

Specification of Letters Patent. Patented Jan. 30, 1917.

Application filed December 8, 1915. Serial No. 65,809.

To all whom it may concern:

Be it known that I, JOHN G. VENN, a citizen of the United States, residing at Jackson, in the county of Jackson and State of Michigan, have invented certain new and useful Improvements in Spring Structures, of which the following is a specification.

This invention relates to spring structures.

10 One object is to provide a base frame for spring structures to which spring supporting wires and upholstered covering facings may be readily secured.

Another object resides in the provision of 15 a base frame for spring structures provided with a plurality of apertures through which suitable fastenings may be passed for the purpose of securing the lower edges of the side facing of the upholstered covering to 20 the base frame.

With the above and other objects in view, the present invention consists in the combination and arrangement of parts hereinafter more fully described, illustrated in the accompanying drawings, and particularly pointed out in the appended claim, it being understood that changes may be made in 25 the form, size, proportion and minor details without departing from the spirit or sacrificing any of the advantages of the invention.

In the drawings: Figure 1 is a transverse sectional view from side to side. Fig. 2 is an inverted plan view of a spring structure 35 illustrating my invention with the springs of the structure removed. Fig. 3 is a detail perspective view of a portion of the base frame. Fig. 4 is a detail perspective view of one of the fastenings.

Referring now more particularly to the accompanying drawings the base frame A 40 may be of any suitable form. As shown, it consists of a continuous side flange portion 5 having a plurality of apertures 6 and a continuous bottom flange portion 7, there being 45 formed a continuous internal groove 8 at the juncture of the side and bottom flanges 5 and 7 to receive the ends of the spring supporting wires 9 which may be secured firmly 50 in the groove 8 by deflecting, bending or otherwise manipulating the inner edges of the bottom flange 7 to cause the same at intervals to be upset for the purpose of overlapping the ends of the spring supporting 55 wires 9, as clearly shown in the drawings.

It is immaterial, however, as to how the supporting wires are secured to the base frame.

Springs 10 are secured to the spring supporting wires 9 in any suitable manner, preferably by means of clips 11, with the border springs having an upper frame or edge wire 12 secured thereto by means of suitable clips 13 or in any other suitable manner, the frames being both of substantially the same size.

60 The spring structure above described is produced as an article of manufacture which is later upholstered in various ways in the same place where manufactured or in some other place to which the same may have been transported. The upholstering process under some methods consumes considerable time and has not always been satisfactory. In any event, it is the practice to first build 65 the spring structure and later upholster the same, either at the place of manufacture of the spring structure or at some other place. To this end, I provide a spring structure to which the upholstered covering may be readily secured either at the place of manufacture of the spring structure or at some other place, as may be desired.

70 As for the upholstering material, the seat portion 14 may be of any suitable material and has side facings 15 secured thereto. 75 The side facings preferably have their lower edges overlapped, as indicated at 16 to reinforce the lower edges and the lower overlapped edges are secured together by a seam to further reinforce the same. The upholstered covering thus formed, that is, including the seat portion and the side facings, is slipped over the spring structure until the lower reinforced edges of the side facings are brought into overlapping relation with the said flange portions 5 of the base frame, covering the aforesaid apertures 6 in the continuous side flange of the base frame.

75 To effectually secure the lower edge of the side facings to the base frame, I preferably employ suitable fastenings 18 of a peculiar form and which are adapted to pierce the side facings immediately above the aforesaid seam 17 and pass through the aforesaid 80 apertures 6 in the base frame. These fastenings may be of any suitable character but, as shown, they may be each formed of a single piece of sheet metal B and bent to provide 85 a square or other head 19 and two 90

prongs 20, each of which may have its lower edge bifurcated to form sharp points 21 to facilitate passing of the fastenings B through the upholstered material and when 5 the fastenings have been passed through the upholstering material above said seam and through said apertures 6 in the base frame, the prongs 20 may be readily and quickly bent back against the inner face of the continuous side flange of the base frame.

I double the material of the lower edge of the facings at their lower edges and seam the same to reinforce the material so as to avoid possibility of accidental tearing of 15 the facings at the points where the fastenings B pierce the same. To further obviate possibility of tearing I preferably pass the prongs 20 of the fastenings through the facings above the seam.

20 What is claimed is:—

A spring structure comprising a base frame composed of a strip of material in-

cluding an upstanding flange provided with relatively small, spaced apertures, springs mounted on the frame, an upholstered covering including a seat portion and a skirt, the skirt having its lower edge folded inwardly and seamed adjacent the lower edges of the skirt and its folded portion, and separate headed fastening passed through the folded portion of the skirt immediately above the seam and inwardly through said apertures and upset against the inner face of the upstanding flange of the base strip, the inner faces of the heads of the fastenings binding the skirt against the upstanding flange of the base strip.

In testimony whereof I affix my signature in the presence of two witnesses.

JOHN G. VENN.
